UNITED STATES PATENT OFFICE.

WILLIAM C. HOMAN, OF MERIDEN, CONNECTICUT, ASSIGNOR TO THE
EDWARD MILLER & COMPANY, OF SAME PLACE.

DESIGN FOR A LAMP-BURNER.

SPECIFICATION forming part of Design No. 21,534, dated May 10, 1892.

Application filed April 18, 1892. Serial No. 429,676. Term of patent 14 years.

To all whom it may concern:

Be it known that I, WILLIAM C. HOMAN, of Meriden, in the county of New Haven and State of Connecticut, have invented a new 5 Design for Lamp-Burners; and I do hereby declare the following, when taken in connection with accompanying drawing and the letters of reference marked thereon, to be a full, clear, and exact description of the same, and 10 to which said drawing constitutes part of this specification and represents a view in perspective of the burner.

This invention relates to a design for a lamp-burner; and the design consists in the configuration thereof, as shown in the accompanying illustration. In outline the lamp-burner is circular in transverse section and has a low convex perforated cone A, the lower and larger end whereof is represented as rising 15 sharply from the gallery B at a point well within the edge of the same. Below the said gallery the burner has the representation of a fillet C, below which is a perforated convex band D, merging at its lower end into an 20 other fillet E, below which there is a vertical perforated band F, which terminates in a fil- 25

let G, below which there is a collar or neck H. The larger end of the said concave band is uppermost and it extends in its lines beyond the lines of the larger lower end of the 30 cone. Fingers I, slightly bowed longitudinally, rise from the outer edge of the gallery.

The leading feature of the design is a lamp-burner having the representation of a low convex cone, the larger lower end whereof 35 rises sharply from the burner-gallery at a point well within the outer edge thereof, a convex band located below the said gallery and having its upper end uppermost and extending beyond the lines of the larger lower 40 end of the cone, and a vertical band located below the said convex band.

I claim—

The design for a lamp-burner, as herein shown and described. 45

In testimony whereof I have signed this specification in the presence of two subscribing witnesses.

WILLIAM C. HOMAN.
